tion

Application June 8, 1934, Serial No. 729,655

5 Claims. (Cl. 66—24)

This invention relates to improvements in knitting machines.

The primary object of this invention is the provision of improved web holding means for manipulating the stitch loops of fabric upon knitting machines for the purpose of changing the character of the knitted fabric.

A further object of this invention is the provision of an improved instrumentality for transferring a stitch loop from one needle or element to another needle or element.

A further object of the invention is the provision of an improved means for transferring the stitch loops of seamless fabric from dial needles 15 of a circular type of knitting machine to the cylinder needles thereof, at the time of transferring from rib knitting to plain knitting; the machine being of the general character set forth in my co-pending application Serial No. 558,798.

20 A further object of this invention is the provision of an improved transfer instrument cooperatively associated with a dial latch needle in such manner as to effectively transfer stitch loops from the dial needles to the cylinder needles.

25 A further object of this invention is the provision of an improved knitting machine having a dial provided with a set of needles and a cooperating set of transfer bits associated respectively therewith in such manner that both the dial 30 needles and transfer bits are cooperatively actuated by cam means disposed at the same side of the dial in order to effect transfer of stitch loops to cylinder needles.

35 Other objects and advantages of the invention will be apparent during the course of the following detailed description.

In the accompanying drawings, forming a part 40 of this specification, and wherein similar reference characters designate corresponding parts throughout the several views,

Figure 1 is a vertical cross sectional view taken through a circular rib knitting machine of the general character set forth in my co-pending application above referred to, but having the improved stitch transfer means associated with the dial thereof.

45 Figure 2 is a plan view of a knitting machine dial bed having the needles and transfer bits supported operatively therein; the dial cap cam grooves and parts being shown in dot and dash lines.

50 Figure 3 is a view of the cam structure of the dial cap; the latter being inverted from its normal position.

55 Figures 4 to 9 inclusive show progressive steps

in the stage of transferring a loop from a dial needle to an adjacent associated cylinder needle.

Figure 10 is an enlarged view showing a needle and its cooperating transfer bit in association within a guide groove of the dial bed. 5

In the drawings, wherein for the purpose of illustration is shown only a preferred embodiment of the invention, the letter A may generally designate a knitting machine, which may include a frame B, a cylinder C; a dial construction D; a set of cylinder needles F; a set of dial needles consisting of a plurality of latch needles, and a set of transfer bits or implements individually associated with the dial latch needles. 10

The knitting machine is preferably of the rotary cylinder type, although the improved bit or instrumentality for manipulating stitch loops may be used wherever it is desired to manipulate or transfer stitch loops from one needle or implement to another needle or implement. The knitting machine as to operating characteristics is clearly detailed in my co-pending application above referred to, and for the purpose of this invention it is suffice to say that the cylinder A has the usual grooves therein for receiving the 15 cylinder needles F, which are preferably of the latch type. The cylinder grooves may also receive jacks 20, and cam means may be provided as set forth in my above mentioned co-pending application for alternately dividing the cylinder 20 needles so that stitch loops may be transferred from the dial needles to the alternate cylinder 25 needles (ordinarily inactive during rib knitting) when it is desired to transfer from rib knitting to plain or other knitting accomplished solely or 30 almost solely upon the cylinder needles. Of course the cylinder has associated therewith the usual web holders and operating means, and feed fingers 21 for feeding yarn to the cylinder and dial needles may be provided in any desired 35 number. 40

The dial construction D includes the usual dial bed 25 keyed as at 26 to a drive shaft 27 arranged concentric to the cylinder, as described in my co-pending application above mentioned. The 45 dial bed 25 is of course provided with radial grooves within which the dial latch needles 27 are reciprocably slidable. In each groove of the dial bed, adjacent each of the needles 27, there is also disposed one of the stitch transfer implements or bits 28. In a rib knitting machine these dial needles 27 would of course be sub-divided into long and short butt needles; substantially one-half of them being long butts and the remainder short butts for well known purposes. 50 55

The dial needles are not operative upon the knitting yarn during the knitting of plain or other knitting which is accomplished solely or almost wholly upon the cylinder needles. However, during rib knitting of seamless fabric the alternate cylinder needles are elevated into position to take the knitting yarn. The remainder of the cylinder needles are inactive in the grooves of the cylinder, as has been described in detail in my co-pending application above mentioned. It is the purpose of this invention to provide an improved instrumentality to properly project and dispose the stitch loops hung on the dial needles in association with the dial needles so that the stitch loops hung upon the dial needles may be transferred to the alternate cylinder needles which are inactive during the knitting of ribbed fabric. Of course the improved stitch loop manipulating element or bit is capable of other uses than that specifically set forth.

The dial construction D also includes the dial cap 30 having an outer circular groove 31 on the under surface thereof concentric with the axis of rotation of the dial for receiving the butts of the dial latch needles 27. A second and inner concentric groove 32 is likewise provided for receiving the butts of the stitch loop manipulating bits or implements 28. Depressible cams 34 and 35 are reciprocably mounted upon the dial cap 30, actuated in a manner which has been specifically described in my copending application above referred to for the purpose of shunting the butts of the dial needles 27 into needle projecting cam grooves 37 and 38 so that the dial needles are projected into yarn receiving relation, or for other purposes. Of course these cams 34 and 35 are operated by suitable means so that they may take the long and short butts of the dial needles as selected and desired.

A depressible cam 39 is similarly provided in cooperation with the transfer bit butt groove 32, depressible in a manner such as set forth in my co-pending application above mentioned for the purpose of directing the transfer implements or bits radially outward in cooperative relation with the dial needles, as projected by the cam 35 and groove 38 so as to position the stitch loops hung on the dial needles in proper transfer relation with those alternate cylinder needles which are inactive during rib knitting.

Referring specifically to the construction of the transfer bit 28, the same includes the flat body 40 which is relatively thin and adapted to slide alongside of a needle 27 in one of the dial bed grooves. Each bit body 40 has a butt 41 thereon which may be long or short, as desired. At its extreme forward end the transfer bit or member is provided with a stitch loop manipulating point or projection 43, which moves into the stitch loop hung on the dial needle so that upon projection of the bit the stitch loop may be moved against the shoulder 45 at the fore end of the bit in order to cause proper projection of the stitch loop into associated transfer relation with the proper cylinder needle. This pointed projection 43 is inclined downwardly below the edge 47 at the bottom of the bit body 40, so that when the transfer instrument or bit 28 is disposed in the dial groove the pointed fore end of the stitch loop projection 43 slides on the bottom of the dial bed groove and the edge 47 is spaced slightly above the bottom of this dial bed groove, as shown in Figure 10, obviously for the purpose of insuring that the bit projection 43 will always lie in position to properly coop-

erate in entering the stitch loop hung on the dial needle cooperating therewith. Rearwardly of the shoulder 45 each transfer bit is concavo-convexly formed to provide a cylinder needle entry groove or opening 48 facing the complementary dial needle 27 associated therewith.

As shown in Figure 2 of the drawings a dial needle 27 and one of the implements 28 are disposed in each of the dial bed grooves. The fore ends of these grooves are suitably widened and formed in order to properly accommodate the fore ends of the needles and bits, so that the concavo-convex bulge of the bit may be slid into the groove as well as projected therefrom.

It is believed that the operation to effect transfer will be apparent from the enlarged views of the parts shown in Figures 2 and 4 to 10 inclusive. The direction of rotation of the dial and cylinder is shown in Figures 2 and 3 of the drawings (see arrows).

In order to effect transfer of the stitch loops hung on the dial needles onto the cylinder needles which are inactive during rib knitting the cam 39 is moved into position to engage the butts 41 of the transfer implements 28. This cooperatively projects the stitch loop entering and lifting projections 43 at the fore ends of the bits. It should be noted that during normal rib knitting the extreme ends of the bit projections 43 lie rearwardly of the hook ends of the dial needles, so as not to interfere with rib knitting and the stitches hung thereon. However, operative positioning of the cam 39 will move the pointed bit ends 43 forwardly into the stitch loops hung on the respective dial needles. In Figure 4 is shown a bit and dial needle in normal position with respect to each other, and one of the cylinder needles. In Figure 5 is shown the stitch loop transfer bit at the start of its projected movement by the cam 39, showing how the end or point 43 thereof enters the stitch loop 60 which is hung on the dial needle and associated therewith. In Figure 6 is shown the bit 28 fully projected by the cam 39 with the stitch loop 60 lifted and projected into position so that the cylinder needle F may be elevated into the slot or opening 48 of the bit. In this position it is noted that the stitch loop is held by the hook end of the dial needle at one side of the bit so that the cylinder needle may properly slip into the stitch loop, and the stitch loop at the opposite side engages above the convex side of the bulge producing the slot or opening 48 in order that the stitch loop is positively spread to permit entry of the cylinder needle F. The cylinder needle elevating cam is shown at 70 in Figure 1.

It is not thought necessary to describe the cooperative elevation of the cylinder needles, normally inactive during rib knitting, in order to effect transfer of stitch loops from the dial needles to such inactive cylinder needles, since such operation has been specifically described in my co-pending application above referred to and the cooperative elevation of these alternate inactive cylinder needles in order to take the stitch loops off the dial needles may be similarly followed, so far as the present invention is concerned.

In Figure 7 it is shown that the dial needles are projected after the associated bit structure 28 has advanced to the peak end of the cam mechanism associated therewith, for the purpose of moving the latch behind the stitch loop. This is obviously controlled by the cam 35 and the cam groove 38, and thereafter the dial needle as well

as the associated bit 28 are retracted. There is a certain amount of springiness at the bit end adjacent the hook of the dial needle, so that they may be readily retracted and spread with the cylinder needle disposed between them, as is shown in the cycle of operation represented in Figures 7, 8 and 9 of the drawings. The stitch loop 60 having been transferred to the cylinder needles, the bits as well as the needles of the dial 10 construction may be inactively buried in the dial bed until such time as it is desired to project the dial needles for again taking the knitting yarns.

Many varieties of knitting may be accomplished upon the knitting machine, and the cooperative 15 use of the bit and dial needle structure is not necessarily limited to a stocking knitted to produce ribbed work or plain knitting.

It is to be noted that the dial needles and bits are compactly associated in complementary relation in the radial grooves of the dial bed and in such manner that the cam means for cooperatively actuating both the bits and the dial needles is located upon a single dial cap, so that the dial structure conforms to conventional dial construction except for the cooperative arrangement 25 of cam grooves in the same dial cap.

The improved implement may be made of steel or any other material found desirable. All of the parts thereof are preferably integral so that the 30 bit is of one-piece construction.

Various changes in the shape, size, and arrangement of parts may be made to the form of invention herein shown and described, without departing from the spirit of the invention or the 35 scope of the claims.

I claim:

1. As an article of manufacture a transfer bit for knitting machines comprising an elongated narrow body having a cam actuated butt thereon and provided at its fore end with a stitch loop 40 entering projection extended at its free end downwardly below the adjacent lower edge of said body, said bit at the juncture of the body with the projection having a stitch loop anchoring 45 shoulder.

2. As an article of manufacture a transfer bit for knitting machines comprising an elongated narrow body having a cam actuated butt thereon and provided at its fore end with a relatively long 50 straight stitch loop entering projection aligned with the body and extended downwardly below the adjacent lower edge of said body, at its free end, said bit at the juncture of the body with the projection having a stitch loop anchoring shoulder, said bit body rearwardly between said shoul-

der and the butt having a laterally disposed offset defining a cylinder needle entering eye.

3. In a knitting machine dial construction for transferring stitches from dial needles to cylinder needles, the combination of a dial bed having slots 5 therein, a set of needles for said slots, a cam for projecting the needles into stitch loop shedding relation, a set of stitch transfer members disposed individually in cooperating relation in the slots with said needles, and cam means for projecting said bits into stitch holding and cylinder needle transfer position in advance of the projection of said needles into their latch shedding positions by the cam means first mentioned and while the hooks of the needles still hold the stitches to 15 be transferred.

4. In a dial construction for a knitting machine adapted to transfer stitches from dial needles to cylinder needles the combination of a dial bed having slots therein, a set of needles for said slots, 20 a cam for projecting the needles into latch shedding position, a set of stitch transfer members disposed individually in cooperating relation in the slots with said needles, and cam means for projecting said bits into stitch transfer position, 25 each of said transfer members comprising an elongated narrow body having a cam actuated butt thereon and provided at its fore end with a lateral offset providing a cylinder needle entering opening facing the respective dial needle associated in the slot therewith, said transfer member beyond the said offset having a stitch loop entering projection extended downwardly at its free end below the adjacent lower edge of said body whereby said projection at its end will ride 30 on the bottom of the slot in which the transfer member is positioned with the said adjacent lower edge of the transfer bit spaced from the bottom of said slot for a distance rearwardly of said point 35 end of said projection.

5. In a dial construction for a knitting machine the combination of a dial bed having slots therein, a set of latch needles, one for each slot, a set of transfer bits, one for each slot in adjacently associated relation with the respective needle 45 therein, cam means for projecting the transfer bits while the latch needles are retracted so that the transfer bits pick up the loops hung on the respective needles and extend them taut beyond the dial bed into a transfer relation with receiving cylinder needles, and cam means to then project the latch needles into latch shedding position, both of said cam means retracting the bits and needles at substantially the same time.

HARRY McADAMS. 55
